UNITED STATES PATENT OFFICE.

GEORGE E. AVERILL, OF CLEVELAND, OHIO, ASSIGNOR OF ONE-HALF
TO HARRY S. WRIGHT, OF BUFFALO, NEW YORK.

BOILER-TUBE BLOWER.

SPECIFICATION forming part of Letters Patent No. 791,996, dated June 13, 1905.

Application filed November 7, 1904. Serial No. 231,681.

To all whom it may concern:

Be it known that I, GEORGE E. AVERILL, a citizen of the United States of America, and a resident of Cleveland, Cuyahoga county, and 5 State of Ohio, have invented certain new and useful Improvements in Boiler-Tube Blowers, of which the following is a specification.

This invention relates to boiler-tube blowers; and it consists of a steam-pipe so constructed and applied to a boiler that the engineer can at any time easily and readily blow out the tubes and prevent the accumulation of soot or scale therein.

The invention consists of a steam-pipe centrally located in the boiler, provided with a perforated head on its inner end, and adapted for injecting steam into the rear ends of the tubes for ejecting the soot out of the forward ends of the tubes into the smoke-stack.

20 In the annexed drawings, which illustrate my invention, Figure 1 is a side elevation of a boiler and stack, partly in section, showing the blowing device attached. Fig. 2 is a longitudinal section of the perforated head, and 25 Fig. 3 is a sectional view of a flexible joint on the front end of the steam-pipe.

A represents a horizontal tubular boiler, and B B the tubes.

C is a pipe located in the center tube and is 30 supported in perforated rings or collars D D, fixed in the tube, in which it may have slideable movements.

E is a perforated head mounted on the inner end of pipe C. The head is made in two 35 parts, each part having a screw-threaded neck, by means of which they are fixed onto the pipe, which has two screw-threaded surfaces e e. Between said screw-threaded surfaces the pipe is perforated to admit steam into the 40 chamber in the head, from which the steam is discharged through diagonal perforations F F in said head. The steam thus discharged is directed into the rear ends of the tubes, as shown by the arrows.

G is a flexible elbow on the front end of the 45 pipe C for connecting it to a vertical steam-pipe H, which will permit the pipe C to be moved in and out without binding of said pipe in its bearings D D. Said elbow consists of two members g g', coupled by a union-nut J. 50 The part g has an outside screw-thread which screws into the inside of part g', which also has an outside screw-thread, upon which the nut J is screwed. K is a packing-ring in said nut J. 55

It will be seen that with the pipe in the position shown in the drawings that the steam will reach the outer circle of tubes and that by drawing the pipe forward the steam can 60 be directed into the inner circle of tubes, and thus make the device available for blowing out all the tubes in a quick and easy manner.

Having described my invention, what I claim, and desire to secure by Letters Patent, 65 is—

1. In a boiler-tube blower, a pipe slidably supported in the center of the boiler, a chambered head having diagonal perforations, mounted on the inner end of said pipe, perforations in said pipe within the head, and adapted to inject steam into the rear ends of the tubes, substantially as described.

2. In a boiler-tube blower, a pipe slidably supported in the center of the boiler, a chambered head having diagonal perforations, 75 mounted on the inner end of said pipe, perforations in said pipe within the head, and a flexible elbow on the forward end of said pipe, and adapted for adjusting the pipe and its head to direct the injection of steam into all 80 the tubes, substantially as described.

Signed by me at Cleveland, Ohio, this 27th day of October, 1904.

GEO. E. AVERILL.
